United States Patent Office.

PETER MURPHY, OF NEW YORK, N. Y., ASSIGNOR TO E. AND H. T. ANTHONY & CO., OF SAME PLACE.

Letters Patent No. 99,462, dated February 1, 1870.

IMPROVEMENT IN PHOTOGRAPHIC-PRINTING FRAMES.

The Schedule referred to in these Letters Patent and making part of the same.

To all whom it may concern:

Be it known that I, PETER MURPHY, of the city and State of New York, have invented an Improvement in Photographic-Printing Frames for porcelain or glass pictures; and I hereby declare the following to be a correct description of the same.

This invention has for its object the securing of the porcelain or glass plate to the swinging back of the printing-frame, so that the process of printing can be observed from time to time. This has usually before been done by adhesive material, or by a costly exhausting-device, both of which are liable to lose their hold, especially when employed with the heavy white glass now usually made use of.

My invention consists in a clamping segmental button, taking over the corner of the porcelain or glass, to hold the same, or when slackened and turned aside, allowing the removal or insertion of the plate for the picture, the said segmental button being combined with the swinging back and plate-holding and printing-frame.

In the drawing—

a represents the frame, with the glass *b*;
c, the back of the frame, hinged, at 2, to the strip *d*, that is hinged to the frame *a*, at 4, so as to allow of the introduction of any desired thickness of plate; and
ee are the bow-springs passing under flanges upon *a*.

These parts, thus far described, are of any desired size and construction, and being well known, do not require further explanation.

I have shown in Figure 1 only a portion of the upper side of the printing-frame, and, in Figure 2, a section at the line *xx*.

My clamping segmental buttons are so placed as to

act at two or more places upon the surface of the plate, near the corners or edges.

Each clamping segmental button is made with a stem, *i*, passing through the back *c*; and provided with a thumb-nut, *k*, at the outer end, and a segment of a disk, *o*, at the other end, as seen in fig. 1, so as to form a button to take over the edge of the plate *l*, and hold the same firmly to the back *c*. When the plate is to be removed, it is only necessary to loosen the nut *k*, and turn the disk *o* around from off the plate *l*.

The negative-glass, *n*, is to be held upon the glass *b* by strips of pasted paper, or other adhesive substances, as usual, but the corners should be removed, as shown, to give room for the segmental button *o*, so that the surfaces of the plates can come into contact.

I am aware that clamps have been employed in printing-frames, the same acting against the edges of the glass or across the ends. These clamps, however, are not as convenient for inserting or withdrawing the plate, or else do not hold the same with sufficient firmness. By the use of segmental disks, as the button-heads at the end of the clamping-screws, that are applied at two of the corners, the plate is held very firmly, but can easily be removed.

I claim, as my invention—

The clamping segmental button formed on the stem *i*, nut *k*, and segmental disk-head *o*, in combination with the swinging back *c*, of a photographic-printing frame, as and for the purposes set forth.

Dated the 26th day of November, A. D. 1869.

PETER MURPHY.
